Samuel B. H. Vance, of New York, N.Y.

Assignor to

Mitchell, Bailey & Co. of Connecticut.

Letters Patent No. 778, Dated April 8, 1856.

The Schedule referred to in these Letters Patent, and making part of the same

To all whom it may concern:

Be it known that I, Samuel B. H.
Vance, of the City, County and State of New York, have invented an ornamented fixture which is intended as a chandalier, the configuration of which and the ornaments thereon, constitute a new and original design; and I do hereby declare that the following is a full and exact description thereof, reference being had to the accompanying drawing, and to the letters of reference marked thereon, which make a part of this specification.

My fixture is so constructed as to be easily modified, and adapted to the use of gas, oil or any other illuminating material.

Fig. 1. is a view of the chandalier, with three branches.

Fig. 2, is an under view of one of the chimney or glassholders.

In Fig. 1. A. is a socket screwed upon the top of the column and by which the fixture is suspended, a, is a round ornamented molding attached to and surmounting the turned ornament B, c.c, are two of three ornamental rosettes attached to the turned ornament B, the whole forming the canopy of the chandalier. E, is an ornament of triangular shape attached to and surrounding the tubing rod D, D. F,F,F', is an ornamented vase about midway of which are attached ornamental scroll formed branches or brackets G,G.

On the outer end of the branches is affixed an ornamental glass or chimney holder H,H.

Attached to and directly under the vase is a large turned ornament of a bulbous shape, as shown at I, on the upper and lower sides of which are ornamental moldings K,K. U,U,U, are three ornaments each composed of five rosettes, the centre rosette being placed in bold relief; at the bottom of the bulbous shaped ornament is a small turned ornament m, at the lower end of which is an ornamented rosette,

n, all as shown in this figure.

What I claim as my invention, and desire to secure by Letters Patent, is the design, configuration and arrangement of the several parts and ornaments as herein set forth, forming a new and original design for a chandelier, with three branches or burners
